UNITED STATES PATENT OFFICE.

FRANCIS KING, OF SAN FRANCISCO, CALIFORNIA.

MASSAGE-MACHINE.

SPECIFICATION forming part of Letters Patent No. 687,243, dated November 26, 1901:

Application filed March 21, 1901. Serial No. 52,352. (No model.)

To all whom it may concern:

Be it known that I, FRANCIS KING, a citizen of the United States, residing at San Francisco, in the county of San Francisco and 5 State of California, have invented certain new and useful Improvements in Massage-Machines, of which the following is a specification.

My invention relates to improvements in 10 massage-machines; and the object of my invention is to provide an apparatus by means of which the movements used in massage treatment may be conveniently obtained from a source of power other than that of the 15 muscular strength of the operator and may be conveniently and effectually administered to the patient.

My invention therefore resides in the novel 20 construction, combination, and arrangement 25 of parts for the above ends hereinafter fully specified, and particularly pointed out in the claims.

In the accompanying drawings, Figure 1 is 25 a perspective view of my improved machine. Fig. 2 is an enlarged longitudinal section 30 through the end of the shaft, the rotation of which produces the rapid mechanical vibrations. Fig. 3 is a similar view showing a 35 modification. Fig. 4 is a cross-section on the line A A of Fig. 2. Fig. 5 is a plan view of the hand-plate or terminal. Fig. 6 is a side 40 view thereof. Fig. 7 is a cross-section thereof. Fig. 8 is a perspective view of the belt 45 used in connection with my apparatus. Fig. 9 is a top view of a modified form of sleeve. Fig. 10 is an end view of the same. Fig. 11 50 is a perspective view of a modified form of the device. Fig. 12 is an enlarged side view 55 of a portion of the apparatus operated from the end of a flexible shaft. Fig. 13 is a section 60 of the same. Fig. 14 is a side view showing 65 a modification of the connection to the hand-plate or terminal. Fig. 15 is a section 70 of the same. Figs. 16 and 17 are sections 75 showing modifications of the device. Fig. 18 80 is a perspective view of the apparatus, showing the two belts attached thereto for torsional vibration. Fig. 19 is an enlarged side 85 view of a portion of the apparatus, and Fig. 90 20 is a front view of a modified form of the 95 device having only one shaft.

Referring to the drawings, upon a suitable

bed-plate are mounted a standard *a* and motor *b*, from which latter power is transmitted to a shaft *c*, rotatably mounted in the upper 55 end of the standard *a*. The shaft *c* carries at each end a disk *d*, in which is formed an undercut diametral groove *e*. The ends of said groove are closed by fixed blocks *f*, leaving a space for the adjustment to and fro of 60 a block *g*, having beveled sides *h*. Into said block *g* is screwed the end of a spindle *h*, upon which is passed a thimble *i*, having a flange *j* abutting against the disk *d*. Over 65 said thimble *i* is then passed a sleeve *k*, having downwardly-extending ears *o*. By screwing up a nut *m* on the end of the spindle *h* said spindle is moved outward and the block *g* is clamped in the groove *e* in any desired 70 position.

In the modification shown in Fig. 3 the spindle *h* is hollow and threaded internally, and through said threaded perforation is screwed a pin *n*, the end of which abuts against the bottom surface of the groove *e*, and so tends 75 to press the spindle outwardly and the block *g* against the sides of the groove and clamp it in position.

The ears *o* are bored, as at *p*, and a bolt *q* is passed through said apertures and through 80 a screw-eye *r*, which rests between the ears *o*, upon which screw-eye is screwed a rod *s*, attached to a helical spring *t*, to the other end of which spring is attached a handle *u*. A nose *v* acts as a stop to prevent the swinging 85 of the screw-eye to such an extent that the part carried thereby would strike the disk *d* on that side. It will be understood from the above that the machine normally carries a helical spring on each side suspended in the 90 manner above described from the shaft *c* and that to the lower ends of said spring may be attached the various devices for treatment by massage. One of these devices comprises a handle *w*, carrying at its lower end a hook 95 *x*. One method of treatment is for the patient to take hold of two such handles, one on each side of the machine, so that the vibrations are imparted to the patient directly through said handles to the patient's hands. 100 In another method of treatment for applying massage to the body and limbs a belt *y* is used, which may be passed around the body or limb of the patient. In another method

of treatment there is provided a rod *z*, one end of which is attached to the lower end of the spring *t*, and the other end carries a hand-plate 1, connected to said rod by means of a 5 universal joint 40.

An important feature of my invention is the construction and arrangement of the hand-plate. Said hand-plate is slightly curved and carries two straps 2 3 of suitable size to 10 be passed around the palm of the hand and the middle finger of the hand, respectively. This construction permits of freedom of manipulation of the face, scalp, or body of the patient by the hand of the operator at the 15 same time that rapid mechanical vibrations are being transmitted therethrough, ranging in speed from three hundred to three thousand five hundred vibrations per minute.

In the modification of the invention shown 20 in Figs. 3, 9, and 10 the sleeve *k* has on each side thereof a lug 4, said lugs entering apertures in the ears 5 of a fork 6. Said fork is of sufficient length to pass around the end of the spindle *h*, so that the rod *s* can now be 25 turned even as far as direct alinement with the spindle. Below the bearings of the shaft *c* are similar bearings for a shaft 7, driven from the shaft *c* by sprocket-wheels 8 and a sprocket-chain 9. By this arrangement 30 two belts may be used at the same time and driven at the same speed. The advantage of this is that the disks of the two shafts *c* 7 may be so arranged that the two belts are moved in opposite directions at the same time. 35 Thus if the two belts be passed around the trunk of the patient the movements thereof are so timed that while the upper belt is moving to the right the lower belt is moving to the left, and vice versa. The result of this 40 is that a torsional movement of great therapeutic value is given to the muscles. The apparatus as prepared for this mode of treatment is illustrated in Figs. 18 and 19, in which two belts *v* are suspended from the handles 45 at the ends of the shafts. It will be seen that the disks *d* are so arranged on the respective shafts that the ends of the belts on the same side of the standard are moving in opposite directions at the same time, thus affording 50 torsional friction to the part operated upon. Intermediate between the shafts *c* and 7 is a shaft 10, which may be driven direct from the motor-shaft. To said shaft 10 is attached a flexible shaft 11, and by this means the massage movement may be applied to the head, 55 trunk, or limbs of a patient in positions and under conditions where terminals connected directly to the shafts *c* and 7 cannot be used. The flexible shaft 11 transmits rotation from 60 the shaft 10 to a shaft 12, connected to a collar 13, rotating on a stud-screw 14, screwed into an extension 15 of a shell 16, said shell abutting against a box 17, secured to the under side of a plate on a knob or handle 18. 65 Said shell 16 surrounds a shaft 19, having secured thereon a miter-wheel 20, meshing with a miter-wheel 21, secured to the collar 13, and

thus the shaft 19 is driven by the shaft 12 and by the electromotor. To the miter-wheel 20 is attached a disk *d*, such as that already described, having the same diametral undercut groove *e*, the fixed blocks *f* therein, and the adjustable block *g*, in the latter of which is screwed a sleeve 22. Said sleeve 22 has an annular rib 23, on each side of which is a ring 75 of balls 24. Surrounding said ring and balls is a shell 25, to which is secured a plate 26. A stud-shaft 27 is screwed into the sleeve 22, and a ring 28 surrounds the head of the stud-shaft 27 and is interposed between said head 80 and the shell 25 and is supported by the plate 26.

28 is a casing which covers the gears 20 21 and protects the hand therefrom.

In operation the handle 18 is held in one 85 hand, while the other is inserted in a strap 29 and applied to the body of the patient. The electromotor having been started, rotation is imparted to the flexible shaft 11, thereby rotating the disk and imparting an orbital 90 motion to the plate 26.

In the modification shown in Figs. 14 and 15 the block *g* carries a stud-shaft 30, upon which is mounted a sleeve 31. Around said sleeve is secured a shell 32, having lugs 33, from 95 which swings a forked support or bail 34 for the handpiece. This construction permits free movement of the hand-plate both about the axis of the shell and about an axis at right angles to said shell. The hand-plate 100 may thus be swung through two right angles while rotary motion is being imparted thereto.

In Fig. 16 is shown a modification in which the handle is elongated and surrounds the shaft which transmits rotation to the disk. 105

In Fig. 17 is shown a modification in which the appliance is used to give percussive treatment, the devices illustrated in Figs. 12 to 16 being adapted to give rotary frictional massage. In this modification the shaft 12 is connected to a bushing 35, rotating in a bearing 36, into which is secured the handle or knob 18. The bushing 35 is secured to the disk *d*, carrying the adjustable block *g*, into which is secured the stud-shaft 30. Around said 115 stud-shaft is a sleeve 31, and around the sleeve 31 is a shell 32, into which is secured a post 37 for the hand-plate.

In Fig. 11 the flexible shaft is shown as attached direct to the shaft of the electromotor. 120 Obviously also the disk for imparting vibration to the massage-terminal may also be attached direct thereto.

I claim—

1. In an apparatus for treatment by massage, a means for producing rapid vibrations, a mechanical extension therefrom, and a means for attaching said extension to the hand of an operator administering the treatment, consisting of a curved plate, and straps 125 secured to said plate, substantially as described.

2. In an apparatus for treatment by massage, a means for producing rapid vibrations,

a mechanical extension therefrom, and a terminal plate, curved in two directions, flexibly connected with said extension, and provided with means for attachment to the hand 5 of an operator, substantially as described.

3. In an apparatus for treatment by massage, a means for producing rapid vibrations, a mechanical extension therefrom, having an interposed elastic section, and a terminal, 10 curved in two directions, and provided with means for attachment to the hand of the operator, substantially as described.

4. In an apparatus for treatment by massage, a means for producing rapid vibrations, 15 a mechanical extension therefrom, a terminal, curved in two directions, provided with means for attachment to the hand of an operator, and a universally-jointed attachment between said extension and said terminal, 20 substantially as described.

5. In a massage-machine, the combination 25 of a rotating shaft, a rod operatively connected with said shaft to be reciprocated endwise thereby, a hand-plate for applying vibrations to the body of the patient through the hand 30 of the operator, and a universally-jointed attachment between said hand-plate and rod, substantially as described.

6. In an apparatus for treatment by massage, a means for producing rapid vibrations, 35 a mechanical extension therefrom, and means for attaching the said extension to the hand of the operator administering the treatment, consisting of a plate, and a flexible strap passing through said plate to form a loop for 40 the hand in front of the plate, substantially as described.

7. In an apparatus for treatment by massage, a means for producing rapid vibrations, 45 a mechanical extension therefrom, and means for attaching said extension to the hand of the operator administering the treatment, consisting of a plate, and a flexible strap passing through slots in the plate and buckled on the rear side of the plate to form a loop on the 50 front side for the hand, substantially as described.

8. In an apparatus for treatment by massage and means for producing rapid vibrations, 55 a mechanical extension therefrom, and a terminal plate flexibly connected at its rear with said extension, and provided in front with pliable means for attachment to the hand of the operator, substantially as described.

55 9. In an apparatus for treatment by massage, a means for producing rapid vibrations, means for transmitting said vibrations to a distant point, and a hand-clamp secured on the distant end of the latter means, said clamp 60 having a broad and substantially rigid surface adapted to rest against the back of the hand, and transmit vibrations thereto, and having a flexible portion adapted to pass in front of the hand and hold it snugly to said 65 surface, whereby the front of the hand may be applied to the body of a patient and the vibrations transmitted thereto through the

hand of the operator, substantially as described.

10. In an apparatus for treatment by massage, a means for producing rapid vibrations, means for transmitting said vibrations to a distant point, and a hand-clamp secured on the distant end of the latter means, said clamp having a portion adapted to engage the 70 back of the hand, and sufficiently rigid to impart vibration thereto and having a portion 75 adapted to pass in front of the hand, sufficiently flexible to permit movement of the hand against the body of the patient, substantially as described.

11. In a massage-machine, the combination 80 of a shaft, means for rapidly rotating the same, a disk carried by said shaft having a diametral groove, a block movable in said 85 groove, means for clamping the block in any desired position therein, a spindle carried by said block, a sleeve on said spindle, and a transmitting device carried by said sleeve and pivoted thereto on a pivotal axis at right angles to said spindle, whereby said transmitting 90 device may be swung to or from the disk, substantially as described.

12. In a massage-machine, the combination 95 of a shaft, means for imparting rapid rotation thereto, a disk on said shaft having a diametral groove, a block movable in said groove, means for clamping the block in any desired position, a spindle extending from said block parallel to said shaft, a sleeve on 100 said spindle, and a forked transmitting device for transmitting the rapid vibrations of said block to the patient, said transmitting device being pivotally connected with said sleeve on an axis passing diametrically through said 105 sleeve at right angles to the spindle, substantially as described.

13. In a massage-machine, the combination 110 of a rotating shaft, a spindle revolved eccentrically by said shaft, a sleeve on the spindle, and a transmitting device carried by said sleeve and pivoted thereto on an axis at right angles to said spindle, substantially as described.

14. In a massage-machine, the combination 115 of a rotating shaft, a device eccentrically connected therewith to be reciprocated by the rotation thereof, and a transmitting device carried by said first device and pivoted thereto on an axis at right angles to the direction 120 of reciprocation, and also at right angles to said rotating shaft whereby when said transmitting device is moved on said pivotal axis, the amplitude of reciprocation so transmitted is varied as desired, substantially as described. 125

15. In a massage-machine, the combination 130 of a rotating shaft, a disk thereon having an undercut diametral groove, a block movable in said groove, a spindle screwed into said block out of line with said shaft, a sleeve on the spindle, a transmitting device carried by the sleeve, and a clamping device having a screw-threaded engagement with the spindle,

to press said block outwardly against the undercut sides of the groove to clamp the block, substantially as described.

16. In a massage-machine, the combination of a rotating shaft, a disk thereon having an undercut diannetral groove, a block movable in said groove, a hollow spindle screwed into said block out of line with said shaft, a transmitting device carried by said spindle for transmitting the reciprocations therefrom and a clamping device consisting of a pin screwed into the perforation of said spindle, and abutting against the bottom of the groove, to press the block outwardly against the undercut sides of the groove to clamp the block, substantially as described.

17. A massage-machine having a standard with two horizontal shafts mounted thereon out of line with each other, geared to rotate in unison, four disks, one mounted on each end of each of the said shafts, and a set of massage apparatus for each shaft, attached eccentrically to the two disks thereon, said

eccentric attachments being so arranged that the two sets of massage apparatus are by the rotation of the disks vibrated in opposite directions at the same time, substantially as described.

18. A massage-machine having a standard with two horizontal shafts mounted thereon out of line with each other, geared to rotate in unison, a set of massage apparatus for each shaft, and eccentric connections between each set and the ends of the corresponding shaft, so arranged that the two sets of massage apparatus are, by the rotation of the shafts, vibrated in opposite directions at the same time, substantially as described.

In witness whereof I have hereunto set my hand in the presence of two subscribing witnesses.

FRANCIS KING.
